Primary Examiner — Garth Rademaker*Assistant Examiner* — Laura H Yu(74) *Attorney, Agent, or Firm* — Hall Estill Attorneys at Law; Mitchell K. McCarthy(57) **CLAIM**

I claim the ornamental design for a shoe fringe, as shown and described.

DESCRIPTION

FIG. 1 is a perspective view of my ornamental design for a shoe fringe;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top view thereof; and,

FIG. 7 is a bottom view thereof.

The broken lines in the figures illustrate portions of the shoe fringe that form no part of the claimed design.

1 Claim, 5 Drawing Sheets(56)
